US00D615367S

(12) **United States Design Patent**
Sierra et al.

(10) **Patent No.:** **US D615,367 S**
(45) **Date of Patent:** ** *May 11, 2010

(54) **FORK**

(75) Inventors: **Diana B. Sierra**, North Bergen, NJ (US); **Adriana Kliegman**, New York, NY (US); **Jeremy Giese**, Norwalk, CT (US)

(73) Assignee: **Playtex Products, Inc.**, Westport, CT (US)

(**) Term: **14 Years**

(21) Appl. No.: **29/314,865**

(22) Filed: **May 6, 2009**

(51) **LOC (9) Cl.** **07-03**

(52) **U.S. Cl.** **D7/653**; D7/664

(58) **Field of Classification Search** D7/368,

D7/395, 401.2, 642-646, 649-654, 660-669, D7/675-676, 683, 688-692, 695-696; D10/46.2; 30/137, 141-143, 147-150, 322-328, 329, 30/340, 342-346; 416/70 R; D21/483

See application file for complete search history.

(57) **CLAIM**

The ornamental design for a fork, as shown and described.

DESCRIPTION

FIG. 1 is a perspective view of a fork of the present disclosure;

FIG. 2 is a top view of the fork of FIG. 1;

FIG. 3 is a bottom view of the fork of FIG. 1;

FIG. 4 is a side elevation view of the fork of FIG. 1; the opposite side view being a mirror image thereto;

FIG. 5 is a front view of the fork of FIG. 1; and,

FIG. 6 is a back view of the fork of FIG. 1.

The broken lines in the drawings illustrating environmental structure or boundaries is for illustrative purposes only and forms no part of the claimed design.

1 Claim, 4 Drawing Sheets
